SILO DOOR FITTING

Frank J. Van Cott and Leon J. Van Cott,
Unadilla, N. Y.

Application September 29, 1941, Serial No. 412,833

13 Claims. (Cl. 20—1.4)

Our invention relates to silos of the type usually found on farms for storage of corn and similar ensilage.

One object of our invention is to provide a new and improved silo and hardware for silo construction which is simple in design, permitting easy erection by persons who may not be skilled mechanics.

Another object of our invention is to provide suitable hardware for silo construction which, when in place on the silo, will not deteriorate under the varied weather and temperature conditions which exist over a period of years of use on a farm, nor from the effect of juices from the ensilage.

Still another object of our invention is to provide hardware for silo structures which has a maximum strength for the use to which it is put but wherein the amount of metal has been reduced to a relative minimum; it being further among the objects to so construct the silo hardware that no metal is allowed to come into contact with the ensilage within the silo.

Also among the objects of our invention is to provide hardware for silo construction which is adapted particularly to fix the width of the doorway so that it does not vary with changes in the season or atmospheric conditions which would have a tendency to swell or contract the staves making up the body of the silo.

A still further object of our invention is to provide a removable door rod for the silo door which can be locked in place but which is easily removed by manipulation of a cam device at the sides of the door, the door hardware being so constructed that the rod spanning the door, together with the circumferential tie rod, cooperate with a fitting used to join the two in such a way that the tendency for the fitting to twist when excessive pressure is applied, is greatly reduced.

With these and other objects in view, our invention consists in the construction, arrangement and combination of the various parts of our device whereby the objects contemplated are attained, as hereinafter more fully set forth, pointed out in our claims and illustrated in the accompanying drawings, in which

Figure 1 shows a partial view of the lower portion of a silo of the type on which silo hardware herein described finds ready use;

Figure 2 is a side elevational view of one type of fitting used to join a circumferential tie rod with a rod spanning the silo doorway;

Figure 3 is a longitudinal view taken on the line 3—3 of Figure 2;

Figure 4 is a cross section taken on the line 4—4 of Figure 2;

Figure 5 is a side elevational view showing a

modified type of door fitting for a removable door rod;

Figure 6 is a top view of the fitting shown in Figure 5;

5 Figure 7 is an end view partly in section showing the relative positions of a circumferential tie rod and a removable door rod prior to locking the door rod in place, and

Figure 8 is a view similar to Figure 7 showing 10 the relative positions of the circumferential tie rod and the door rod has been locked in place.

This is a continuation in part of our co-pending application Serial No. 234,334, filed October 10, 1938, for a Silo construction.

15 Various kinds of silo hardware have been designed and some have been devoted to the purpose of fixing the width of a silo doorway to as nearly a constant dimension as has been practical. Frequently, the hardware used has been extended around the door jamb so that some part or other of the metal comes in contact with the ensilage where it is quite apt to become rusty and consequently rapidly deteriorate. In other cases the fittings comprising the hardware, while providing a means of coupling together the ends of circumferential tie rods, have not taken into consideration the tendency of fittings to twist when the rods are placed under pressure and the prior art has failed to recognize that this constant tendency to twist and untwist as the silo staves swell and contract with changing moisture and temperature conditions is one of the factors which causes eventual deterioration of the silo structure, which becomes apparent after a period of years.

20 On the accompanying drawings, we have used the reference character S to indicate generally a silo and F the foundation therefor. The silo S is composed of a plurality of vertically arranged staves 10 which form a cylindrical wall and terminate in door jamb members 12 between which doors 13 are mounted. The staves 10 have tongue and groove joints at their side edges as shown in Figure 3 and are doweled together by spikes 14.

25 Extending around the silo S are hoops 15 forming circumferential tie rods, and door-front rods 16. These are connected together by tank lugs T and door fittings D. Door fittings D are castings, or the like, having short perforated bosses 17 for receiving the ends of circumferential tie rods 15 and elongated bosses 18 having recesses 18a for receiving the ends of the door-front rods 16. The rods 16, termed door-front or door rods, are in practice not connected directly to the door but rather to the door jambs on opposite sides and merely extend in front of the door. A supporting element 19 bears against the edge of the door jamb. Draw nuts 21 and 22 on the door rods and tie rods respectively engage the ends

30 35 40 45 50 55 60

of the bosses 13 and 17 to draw the hoop assembly tight around the staves of the silo. The door fittings D are secured to the door jamb members 12 by bolts 23 and to the adjacent staves 10 by short nails 24. Bolt heads may be 5 recessed as at 20 on the inner wall and covered with a protective coating 20a.

Heretofore door fittings of the general character thus far described have been used, but when there is sufficient swelling of the staves 10 to 10 entirely take up the space within the silo hoops, the exceptionally great strain applied to the tie rods that extend from one door fitting D around the staves to the other door fitting D, tends to draw on the bolts 23 and nails 24 and move the door jamb elements 12 relative to the door fittings D in a direction toward each other, thus 15 decreasing the distance between the door jambs. This would so tighten the door 13 that it would be extremely difficult to loosen it when desired. The excessive pull might also tend to break the door fittings D.

Our present improvement resides in the formation of a flange 25 (see Figures 2, 3 and 4) on the back of the door fittings D. The flange is vertically arranged and may be embedded into the outside surface of the door jamb members or the adjacent staves. Preferably, it is countersunk in the outer edge of the door jamb member 12, which edge is notched at 26 for this purpose. The flange 25 being mounted in this position is spaced from the door opening and the edge 12a of the door jamb member at the opening is smooth and unobstructed, as shown in Figure 3, so that the door will fit tightly throughout its entire 30 height. Also, the flange and all the door hardware structure is removed from contact with the juices of the ensilage. By being embedded in the wood of the wall, the flange reduces the tendency of the front lug to twist to a minimum and the flange serves as a reinforcing means 35 against breakage of the lug due to strains thereon. Imbedding of the flange in the silo wall also increases the amount of surface against the wood of the wall to counteract the pull on the tie rods.

Considering the operation of the flange 25, it will be obvious that the force of any swelling of the staves 10 is counteracted by the two staves adjacent the door jamb members 12 by pressure of their edges against the adjacent faces of the flanges 25. Thus the flanges serve as a much more effective means to prevent shifting of the door jamb members 12 toward each other than the mere use of the bolts 23 and the nails 24 as heretofore practised. Since the flange 25 prevents twisting of the fitting, the trouble heretofore experienced of the tie rods bending short at the ends of the fittings when tightened, has been eliminated, and the consequent tendency of the door fitting to break has likewise been 40 eliminated.

Figures 5, 6, 7 and 8 show a modified type of door fitting whereby the door rod can be removed and replaced at will. It is contemplated that the door fittings shown in Figures 5 through 8 will be alternated with the fittings heretofore described so that every other door fitting is of the removable type, even though the silo may be large and the tie rods placed somewhat closely together. The removal of a removable door front 45 rod positioned alternately with fixed door rods will in practically all cases be sufficient to make an opening large enough for a man to get inside of the silo. Moreover, the greatest strain which is placed upon the circumferential tie rod and

the fittings occurs when the silo is being filled. After the silo has been filled and the ensilage has stood for a time, it takes a set like a large cheese and the strain on the circumferential tie rods is in time reduced. When the silo is opened and the door removed section by section from the top downwardly toward the bottom, there is no undue strain on the remaining tie rods due to removal of alternate rods across the doorway.

As shown in Figures 5 and 6, the fitting consists of a body generally indicated by the character 35 and is used to connect a circumferential tie rod 15 with a removable door front rod 36. As will be noted, there is a hole 37 extending through a boss 38 on the upper side of the body for reception of the circumferential tie rod 15 which is provided with a threaded end 39 and a nut 40 for holding it in place. On the lower side of the tie rod there is an upwardly curved shelf 41 forming a rounded recess 42 for reception of the door front rod 36. It will be noted also that the door front rod has a threaded end 43 and a nut 44 on the threaded end so that it may be drawn up tightly in place when the silo is made ready for filling.

The fitting 35 is also provided with a flange 45 running crosswise relative to the body of the fitting and vertically with respect to the silo. The flange is similar to the flange described in connection with Figures 1 through 4 and is designed to be received in a corresponding recess 46 in a stave of the silo, as for example at the edge of the stave shown in Figure 6. Contact of the flange with the stave has a tendency not only to maintain the stave in a fixed position but also assists in preventing twisting of the fitting when pressure is applied to the rods 15 and 36 in opposite directions. Bolts 47 and nuts 48 are shown applied to the upper and lower sides of the body, respectively, for fastening the fitting to the wall of the silo.

In order to maintain the quantity of metal in the fitting at a relative minimum without sacrificing the rigidity of the fitting, there are provided lugs 50 and 51. The lug 50, for example, is positioned at the end of an arm 52 so that it extends outwardly along the circumferential tie rod 15. The lug 50 is positioned so that it will bear against the tie rod 15 at a point spaced from the body of the fitting. On the lower side, the lug 51 is on a short extension 53 which is in turn supported jointly by an arm 54, at the lower side between the lug and the shelf 41, and an arcuate arm 55 at the upper side of the body. The contacting faces of both lugs may be slightly curved so that they conform to the circumference of the tie rod and door rod, respectively.

In order to set the door front rod or door rod 60 in place and lock it there while the silo is being filled, there is provided a plate 60, a partial side view of which is shown in Figures 7 and 8, which has an aperture 61 within which the door front rod 36 is permanently positioned. A plate 60 is 65 attached, one at each end of the door front rod, so that one plate will lie outside of the right-hand fitting and another plate will lie outside of the left-hand fitting. It should be noted, of course, that the fitting 35 described above is a right-hand fitting for the right-hand side of the door and that a corresponding left-hand fitting with the parts generally reversed is provided for the left-hand side of the door. In all operative details, the left-hand fitting is the same as the right-hand fitting.

Each plate 60 is provided with a notch 62 and a cam face 63 which, in use, lies adjacent a portion of the circumferential tie rod 15. At its other end the plate is provided with a cutout portion 64 long enough to permit insertion of the fingers of the hand and a curved leg 65 at the end of the recess which in assembled position bears against the outside wall of the silo. The plate 60 is designed to lie against a flat face 66 at the outside end of the fitting so that, in addition to its other functions with regard to locking the door rod in place, it serves in effect as a washer for the nut at the end of the door rod.

In operating the removable door rod, the silo structure is built up as usual with the permanent circumferential tie rods in place. The door fittings 35 are likewise attached to the outside of the silo wall in their proper positions. It will be noted, of course, that the fittings for the removable door rods overlie primarily the door jamb but that a portion of each may overlie the silo stave next adjacent the door jamb. Bolts extending through the door jamb may have the heads recessed into the staves and the recess aperture blocked over with the bolt heads covered on the inside of the silo so that they do not come into contact with the ensilage juices. The nuts 48 secure the body of the fitting to the bolts thus inserted. When the fitting is put into place, the flange 45 is driven into the recess 46 so that the inside surface of the fitting is flush with the silo wall. It will be noted, of course, that the flange extends only approximately half way through the silo staves and is not exposed on the inside wall of the silo.

The circumferential tie rods 15 are attached to the fittings and the nuts 40 drawn up so that the round stave body of the silo is made firm.

Next, a plate 60 is placed one at each end of the door rod 36 and the nuts 44 threaded over the ends of the rod. Then the operator, grasping one of the plates 60 in each hand, places the ends having the notches 62 against the tie rod 15 on each side. As indicated in Figure 7, when the notch 62 rests upon the tie rod, the door rod 61 is positioned at the open end of the rounded recess 42. The opposite end of the plate 60 is then forced inwardly by hand and the locking face 63 serves as a means for camming the tie rod 60 snugly into its position within the rounded recess 42.

After the door rod 61 has been forced into the bottom of the recess, as shown in Figure 8, the locking end 63 bears upon the under side of the circumferential rod 15 and effectively locks the door rod in place. In this position the leg 65 will rest against the outside wall of the silo. The nuts 44 can then be tightened.

Thereafter, should a person attempt to climb the silo by using the door rods as rungs of a ladder, a pull upon the removable door rod in an outwardly or in an upwardly direction will be resisted by the locking face 63 bearing against the tie rod so that the door rod cannot be inadvertently removed or loosened.

After the silo has been filled and it becomes necessary at some later date to gain access, it is necessary only for an operator to grasp the lower end of each of a pair of plates 60 and lift them angularly upward to the position shown in Figure 7. When the plates have been thus lifted upward, the door rod 61 becomes removed from its recess and permits the plates and the attached door rod to be removed from the silo. After this has been accomplished, the doorway of the silo

will be increased in size, permitting easier access to the silo. The door-front rod 35, of course, can be locked in place again at any time by manipulation of the door-front rod and attached plates 60 as has been described above.

There has thus been described silo hardware devices which are simple in their construction and operation sufficient so that they may be readily applied in the field and a silo erected 10 which will be capable of withstanding the deteriorating effects of the ensilage juices and which also will permit ready access to the silo for any necessary unloading or cleaning.

Some changes may be made in the construction and arrangement of the parts of our device without departing from the real spirit and purpose of our invention, and it is our intention to cover by our claims any modified forms of structure, or use of mechanical equivalents, which may 20 be reasonably included within their scope.

We claim as our invention:

1. In a silo structure, a door fitting comprising a body having an aperture for reception of a circumferential tie rod, a relatively flat connecting portion for the outside wall of the silo having extensions overlying a door jamb member and an adjacent stave member and securing means for attaching the body to the silo, a lug on one of said extensions spaced laterally from said aperture positioned for contact with said circumferential tie rod, said body having a recess parallel to said aperture and spaced therefrom in a vertical direction for reception of a silo door-front rod and a lug on the other extension spaced laterally from the recess and positioned for contact with the door-front rod on the side opposite from the corresponding contact location of said first lug with the circumferential tie rod, said lugs engaging the respective rods to minimize resistance to potential twisting of the fitting about a horizontal axis and a flange on the side of said body adjacent the silo extending part way into the silo wall adjacent the door jamb member, said flange providing resistance to potential twisting of the fitting.

2. For use in a stave tank structure having a door opening, a door fitting comprising a body having an aperture for reception of a circumferential tie rod, and a relatively flat contacting portion for the outside wall of the tank, a side opening recess on the body having its axis spaced laterally from and parallel to said aperture, for reception of a door-front rod, a plate having an aperture therein for reception of the door-front rod, said plate having a normal operative position against a side of the body remote from the door opening, said plate having a notch at one end adapted to engage the circumferential tie rod adjacent the fitting body during an initial closing operation, and a cam face on the end of the plate adjacent the recess, having a bearing against the circumferential tie rod when the door-front rod is in normal completed retaining position.

3. For use in a silo structure, a door fitting comprising a body having a horizontal aperture for reception of a circumferential tie rod, a relatively flat contacting portion for the outside wall of the silo and a side opening horizontal recess on the body having its axis spaced laterally from and parallel to the horizontal aperture for reception of a silo door-front rod, and a plate having an aperture therein for reception of the door-front rod, said plate having a normal operation position perpendicular to the silo wall against

a side of said fitting body remote from the silo door, said plate having a cam face on the end of the plate adjacent the aperture therein and having a bearing against the circumferential tie plate when the rod is in normal completed door-front rod retaining position.

4. In a silo structure, a door fitting comprising a body having a horizontal aperture for reception of a circumferential tie rod, a relatively flat contacting portion for the outside wall of the silo and a side opening horizontal recess on the body having its axis spaced laterally from and parallel to the horizontal aperture, for reception of a silo door-front rod, a plate having a hole therein for reception of the door-front rod, said plate having a normal operative position perpendicular to the silo wall against a side of said fitting body remote from the silo door, said plate having a cam face on the end thereof adjacent the hole, bearing against the circumferential tie rod when the rod is in normal completed door-front rod retaining position, and an extension on the plate to provide a hand hold.

5. In a silo structure, a door fitting comprising a body having a horizontal aperture for reception of a circumferential tie rod, a relatively flat contacting portion for the outside wall of the silo and securing means for attaching the body to the silo, an extension on the body overlying the silo wall and an upward side opening horizontal recess on the extension having its axis spaced vertically from and parallel to the horizontal aperture, for reception of a silo door front rod, a plate having a hole therein for reception of the door front rod, said plate having a normal operative position perpendicular to the silo wall against a side of said body remote from the silo door, said plate having a notch at one end adapted to fit over the circumferential tie rod during an initial door opening or closing operation, and a cam face on said plate adjacent the recess therein having a bearing against the circumferential tie rod when the rod is in normal completed door retaining position, and a finger at the lower end of said plate adapted to bear against the silo wall, said plate having a hand aperture adjacent the finger.

6. In a silo structure, a door fitting comprising a body having an aperture for reception of a circumferential tie rod and an elongated recess parallel to and spaced from said aperture, a flat end face on said body intersecting said aperture and said recess, and an arm extending from said body beyond said end face, carrying a lug engageable with said tie rod at a point spaced from said body and on the opposite side of said tie rod from said recess.

7. For use in a silo, a fitting comprising a body with a horizontal aperture therethrough for reception of a circumferential tie rod, said body having a recess formed therein below and substantially parallel to said aperture, opening upwardly and outwardly to receive a removable rod section, said body also having a flat face formed thereon, substantially perpendicular to the axes of said rods, and intersecting both said aperture and said recess.

8. For use in a silo, a fitting comprising a body with a horizontal aperture therethrough for reception of a circumferential tie rod, said body having a recess formed therein below and substantially parallel to said aperture, opening upwardly and outwardly to receive a removable rod

section, and a horizontal extension arm from said body having a lug thereon engageable with the upper surface of the tie rod.

9. For use in a silo, a fitting comprising a body with a horizontal aperture therethrough for reception of a circumferential tie rod, said body having a recess formed therein below and substantially parallel to said aperture, opening upwardly and outwardly to receive a removable rod section, a horizontal extension arm from said body having a lug thereon engageable with the upper surface of the tie rod, and a second arm, extending horizontally from said body in a direction opposite to said first arm, and having a lug thereon engageable with the lower surface of the removable rod.

10. For use in a silo having removable doors, a door fitting comprising a body with a horizontal opening therethrough for reception of a circumferential tie rod, and with a slot therein adapted to receive a door-front rod, and a locking plate adapted to be mounted on a door-front rod, said plate having a notch formed in one end thereof, adapted to engage the circumferential tie rod adjacent the fitting body, during an initial locking movement in which the plate pivots about the tie rod to serve as a lever for forcing the door-front rod into the slot.

11. For use in a silo, a fitting comprising a body with a horizontal aperture therethrough for reception of a circumferential tie rod, said body having a slot formed therein substantially parallel to said aperture, opening upwardly and outwardly to receive a removable rod section, and a locking member having a hole therein through which the removable rod extends, said plate having a notch formed in one end thereof, adapted to engage the circumferential tie rod and pivot thereon when the plate is used as a lever to force the removable rod into said slot, and a cam face on the end of said locking member adjacent the notch, said cam face being arranged to bear upon said tie rod when said member is swung to its extreme locking position.

12. A silo hoop fitting comprising a body having a horizontal aperture therethrough for reception of a circumferential tie rod, a relatively flat contacting portion for the outside wall of the silo, and a recess formed below and substantially parallel to the aperture, opening upwardly and outwardly to receive a removable rod section, said body also having a flat face formed thereon, substantially perpendicular to the axes of said rods, intersecting said aperture and said recess and continued past the plane of said flat contacting portion to form a vertically extending flange engageable with a vertical slot in a side wall member of the silo.

13. A silo hoop fitting comprising a body with an aperture extending horizontally therethrough for reception of a tension rod, said aperture being formed in said body as a channel, open on the side toward the silo, with members bridging said channel adjacent the ends of said aperture and adapted to bear on the outer surface of the silo, a boss on said body offset from said aperture and adapted to receive a second tension rod, and a vertical flange on the side of said body adjacent the silo, constituting an extension of one of said bridging members and adapted to fit in a groove in the silo wall to position said fitting.

FRANK J. VAN COTT,
LEON J. VAN COTT.
